(57) **CLAIM**

I claim the ornamental design for a dehumidifier, as shown and described.

DESCRIPTION

FIG. 1 is a perspective view of a first component of a dehumidifier according to my new design;

FIG. 2 is a view of the first component of the dehumidifier shown in FIG. 1 from the front;

FIG. 3 is a view of the first component of the dehumidifier shown in FIG. 1 from the rear;

FIG. 4 is a view of the first component of the dehumidifier shown in FIG. 1 from the left;

FIG. 5 is a view of the first component of the dehumidifier shown in FIG. 1 from the right;

FIG. 6 is a view of the first component of the dehumidifier shown in FIG. 1 from the top;

FIG. 7 is a perspective view of a second component of the dehumidifier according to my new design;

FIG. 8 is a view of the second component of the dehumidifier shown in FIG. 7 from the front;

FIG. 9 is a view of the second component of the dehumidifier shown in FIG. 7 from the rear;

FIG. 10 is a view of the second component of the dehumidifier shown in FIG. 7 from the left;

FIG. 11 is a view of the second component of the dehumidifier shown in FIG. 7 from the right;

FIG. 12 is a view of the second component of the dehumidifier shown in FIG. 7 from the top;

FIG. 13 is a perspective view of the dehumidifier in a first mode according to my new design;

FIG. 14 is a view of the dehumidifier in the first mode shown in FIG. 13 from the front;

FIG. 15 is a view of the dehumidifier in the first mode shown in FIG. 13 from the rear;

FIG. 16 is a view of the dehumidifier in the first mode shown in FIG. 13 from the left;

(Continued)

FIG. 17 is a view of the dehumidifier in the first mode shown in FIG. 13 from the right;
FIG. 18 is a view of the dehumidifier in the first mode shown in FIG. 13 from the top;
FIG. 19 is a perspective view of the dehumidifier in a second mode according to my new design;
FIG. 20 is a view of the dehumidifier in the second mode shown in FIG. 19 from the front;
FIG. 21 is a view of the dehumidifier in the second mode shown in FIG. 19 from the rear;
FIG. 22 is a view of the dehumidifier in the second mode shown in FIG. 19 from the left;
FIG. 23 is a view of the dehumidifier in the second mode shown in FIG. 19 from the right; and,
FIG. 24 is a view of the dehumidifier in the second mode shown in FIG. 19 from the top.
